UNITED STATES PATENT OFFICE.

CHARLES KERR MARR, OF LONDON, ASSIGNOR TO JONATHAN REDMAN, OF SALEM MILLS, HEBDEN BRIDGE, ENGLAND.

APPARATUS FOR AUTOMATICALLY DISPLAYING ADVERTISEMENTS.

SPECIFICATION forming part of Letters Patent No. 542,802, dated July 16, 1895.

Application filed September 18, 1894. Serial No. 523,384. (No model.) Patented in England September 1, 1893, No. 16,450.

To all whom it may concern:

Be it known that I, CHARLES KERR MARR, gentleman, a citizen of the United Kingdom of Great Britain and Ireland, residing at 5 Milk Street Buildings, in the city of London, England, have invented new and useful Improvements in Apparatus for Automatically Displaying Advertisements, Pictures, and the Like, (which have not been patented in any 10 country except Great Britain and Ireland, by Letters Patent dated the 1st day of September, 1893, No. 16,450;) and I do hereby declare that the following is a full, clear, and exact description of the invention, which will 15 enable others skilled in the art or manufacture to which it relates to make and use the same.

This invention relates to that class of automatically-acting advertising-machines where- 20 in a series of rectangular or other shaped drums or cylinders are used to display advertisements, pictures, and the like, the said drums being periodically rotated through the instrumentality of clockwork mechanism in 25 order to expose to view a number of different advertisements in one and the same space; and the present invention has for its object improvements in the electrical mechanism described in the specification filed under the 30 Letters Patent granted to George Cook and myself, No. 507,785, A. D. 1893, for rotating the cylinders or drums in conjunction with the clock.

As illustrated by the accompanying drawings, Figure 1 is a front elevation of the improved advertising apparatus; Fig. 2, a rear elevation with the back of the casing removed; Figs. 3 and 4, front and side elevations of details of the electrical mechanism, 40 and Fig. 5 the clockwork mechanism and electrical connections.

The improved apparatus consists, as particularly shown by Figs. 3 and 4, of a solenoid A, the two soft iron cores B of which are 45 connected to a frame C constituting a magnet-armature, and which frame is capable of movement in a vertical direction.

The frame C has a pawl D loosely centered on its lower part, and the said pawl has a heel 50 E on it which, in the operation of the apparatus, acts on a number of pins a spaced

at equal distances apart around one face of the periphery of a disk F secured on the spindle of the advertising drum or cylinder G, a similar number of pins b being fixed in 55 the other face with which a tooth made on a loosely-centered lever H engages, so as to prevent the disk F from turning backward. One such solenoid A is provided for each advertising drum or cylinder G in the machine, the 60 number of pins in the disk F corresponding to the number of advertisements, row of pictures, or the like, it is desired to display.

The coils constituting the solenoids A are connected to a battery and in the circuit a 65 clock I is placed, in conjunction with which a contact making and breaking cam or lever J is provided, the said lever having preferably three arms, to each of which one end of a spring J' is attached, the other end being 70 provided with a pin J² projecting through the arm and which, through the action of the clock on whose dial or other spindle the lever is fixed, is caused to periodically make contact with a series of pins K in the circuit, the 75 effect of which is at each contact to raise the frame C carrying the pawl D from the last-operated-on pin in the drum-turning disk F.

Immediately the pin of the spring J' in any arm of the lever or cam J is by the clock 80 moved out of contact with any pin K connected to a solenoid, the circuit is broken and the frame carrying the pawl D drops by its own weight and the drum or cylinder G is turned through an arc so as to display an- 85 other advertisement, picture, or the like.

The cam L, which causes the spring M to transmit the electric current from the battery-wire X to the lever J, is the same as that described in the aforementioned specifica- 90 tion.

Having now described the invention, what I desire to secure by Letters Patent is—

In an automatically acting advertising machine, the combination with the spindle of 95 the advertising cylinder or drum and contact making and breaking appliances operated by clockwork, of a solenoid including the cores B, a frame C constituting a magnet armature and connected to the cores B and capable of 100 a vertical movement, pawl D centered on the lower member of said frame, a disk as F, se-

cured on the spindle of said drum and provided with a series of pins adapted to be acted upon by said pawl when the electric current is transmitted through said solenoid by the 5 action of the clockwork on the contact making and breaking appliances, substantially as set forth.

In witness whereof I have hereunto set my hand and seal this 25th day of August, 1894.

CHARLES KERR MARR. [L. S.]
